Primary Examiner — Patricia A Palasik(74) *Attorney, Agent, or Firm* — Studebaker & Brackett
PC(57) **CLAIM**

The ornamental design for a powered exoskeleton, as shown and described.

DESCRIPTION

FIG. 1 is a front, top, and right side perspective view of a powered exoskeleton showing our new design;
 FIG. 2 is a rear, bottom, and left side view thereof;
 FIG. 3 is a front view thereof;
 FIG. 4 is a rear view thereof;
 FIG. 5 is a top view thereof;
 FIG. 6 is a bottom view thereof;
 FIG. 7 is a left side view thereof;
 FIG. 8 is a right side view thereof;
 FIG. 9 is an enlarged view of FIG. 1 thereof;
 FIG. 10 is an enlarged view of FIG. 2 thereof;
 FIG. 11 is an enlarged view of FIG. 7 thereof; and,
 FIG. 12 is a reference view showing state in use.
 The broken lines in the drawings depict portions of the powered exoskeleton which form no part of the claimed design.
